UNITED STATES PATENT OFFICE.

TOD J. MELL, OF AKRON, OHIO, ASSIGNOR TO THE B. F. GOODRICH COMPANY, OF NEW YORK, N. Y., A CORPORATION OF NEW YORK.

SHEET MATERIAL AND METHOD OF INCORPORATING THE SAME IN A COVERING STRUCTURE.

Application filed April 23, 1926. Serial No. 104,127.

This invention relates to sheet material suitable, for example, to be interposed between a floor and rubber or other floor-covering material thereon.

5 Heretofore felt sheets without a binder or impregnation have been employed as an under layer for rubber and for linoleum flooring and the felt sheets have been secured to the rubber or linoleum flooring and to the 10 floor by the use of adhesives containing water as applied and of such character as to result in damage to the structure by the ingress of water or moisture after the installation has been completed. I also have employed a floor-covering comprising a sheet 15 of rubber secured to a backing sheet of bituminous material, as described in my co-pending application Serial No. 104,126, filed April 23, 1926, which has permitted the use 20 of desirable adhesives which contain quick-drying solvents, such as the usual water-proof linoleum cements, but the product there described for the best results requires 25 that the rubber sheets be vulcanized to their backing sheets, which cannot conveniently be done except with equipment which is not readily available except at the rubber factory, and uneven floors frequently require a 30 sub-layer of such thickness and character that it cannot be conveniently and economically attached to the rubber sheet at the factory and distributed therewith.

35 My chief objects are to provide sheet material adapted to be conveniently secured to a floor or the like and to have a sheet of rubber conveniently secured to its opposite face without vulcanization, as in the laying of floor covering material. A further object is to provide a floor-covering structure or the 40 like of which all of the parts advantageously may be assembled at the place of use.

Of the accompanying drawings:

Fig. 1 is a perspective view of my improved sheet material in its preferred form.

Fig. 2 is a section of the same.

Fig. 3 is a section of a portion of a floor and a floor covering including my improved sheet material thereon.

Referring to the drawings, the improved sheet material comprises a sheet of felt 10,

preferably wool felt, which from one side face thereof to a considerable depth is impregnated, as shown at 11, with a binder, preferably a bituminous binder, adapted to be secured to a floor 12 by an adhesive 55 such as a water-proof linoleum cement adapted to resist the softening and loosening action of water after it has dried.

To an appreciable depth from the opposite face the felt sheet 10 is free of such binder or impregnation, as shown at 13, so that it conveniently and effectively may be secured to an overlying sheet of rubber 14 by the usual water-soluble adhesive.

The felt sheet is secured to the rubber 65 sheet 14 and to the floor 12 by respective adhesives of the characteristics described, with the result that the floor covering, by reason of the binder in the region 11 and the water-resisting adhesive securing it to the floor, is 70 adapted to prevent water or moisture from rising into it from the floor, and the unimpregnated condition of the upper portion of the felt sheet permits a comparatively rapid evaporation of both of the solvents employed 75 in the two different cements.

I do not wholly limit my claims to the specific structure or procedure herein described, as my invention is susceptible of modification and of different applications 80 within its scope.

I claim:

1. In combination with a support such as a floor, a facing sheet, a sheet of fibrous material between the two, the said sheet having 85 its surface portion adjacent the support impregnated with a water-proof binder and a zone nearer its opposite face free of such binder, and a water-proof adhesive securing the sheet to the support.

2. A combination as defined in claim 1 in which the facing sheet is secured to the sheet of fibrous material.

3. The method of making and mounting a covering which comprises producing a 95 sheet of fibrous material with the surface portion of only one side impregnated with a water-proof binder, and thereafter securing the impregnated surface thereof to a surface to be covered by means of a water- 100

proof cement, and securing a facing sheet to the opposite face of the sheet of fibrous material.

4. The method of making and mounting a covering which comprises producing a sheet of fibrous material with the surface portion of only one side impregnated with a water-proof binder, and thereafter securing the im-

pregnated surface thereof to a surface to be covered, by means of a water-proof cement, ¹⁰ and securing a facing sheet to the opposite surface of the sheet of fibrous material by means of a water-soluble adhesive.

In witness whereof I have hereunto set my hand this 16th day of April, 1926.

TOD J. MELL.
